SHOE SEWING MACHINE

Original Filed Jan. 22, 1921 2 Sheets-Sheet 2

INVENTOR:

James H. Reed
By MacLeod, Bahn, Lepel and Duff

UNITED STATES PATENT OFFICE.

JAMES H. REED, OF SWAMPSOFT, MASSACHUSETTS, ASSIGNOR, BY MESNE ASSIGNMENTS, TO UNITED SHOE MACHINERY CORPORATION, OF PATERSON, NEW JERSEY, A CORPORATION OF NEW JERSEY.

SHOE-SEWING MACHINE.

Original application filed January 22, 1921, Serial No. 439,255. Divided and this application filed August 12, 1921. Serial No. 491,694.

To all whom it may concern:

Be it known that I, JAMES H. REED, a citizen of the United States, residing at Swampscott, county of Essex, State of Massachusetts, have invented a certain new and useful Improvement in Shoe-Sewing Machines, of which the following is a specification, reference being had therein to the accompanying drawings.

10 This invention relates to shoe sewing machines of the type shown and described in my prior application for Letters Patent filed January 22, 1921, Serial No. 439,255, of which this case is a division, the machine 15 shown in said application being intended primarily for use in the manufacture of McKay shoes although also capable of use in many other places, as, for example, for stitching along the shanks on the inside of 20 shoes of the Goodyear welt type.

Heretofore in the manufacture of McKay shoes the sole has been stitched to the upper and the insole by a seam located inside the shoe, and, therefore, it has been customary to use a chain-stitch sewing machine. The machine shown and described in my prior application aforesaid sews a lock-stitch seam and has a straight barbed needle and a shuttle supplying a shuttle 30 thread on the outer side of the shoe sole, while on the interior of the shoe there is a cooperating horn and an oscillating looper supplying a cop thread. In accordance with the present invention the horn and 35 looper are of such construction that they can operate in the constricted space inside the toe of a boot or shoe, while a takeup for the cop thread is also associated with the horn, said takeup being sufficiently 40 powerful to sink the locks of the stitches to the desired depth in the outsole.

The more particular objects of the invention, together with means whereby the same may be carried into effect, will best be understood from the following description of one form or embodiment thereof, illustrated in the accompanying drawings, in which:

Fig. 1 is a side elevation, partly in section, of substantially the complete machine.

Fig. 2 is a front elevation of the upper portion thereof.

Fig. 3 is a detail view illustrating the co-operation of the needle and looper.

Fig. 4 is a section on line 4 of Figure 1. 55

Fig. 5 is a section on line 5—5 of Figure 1, showing the operating mechanisms for the takeup and looper.

Referring to the drawings, there is shown at 11 the base or frame of the machine, at 12 the horn or work support, and at 13 the framework of the head. The horn is of a size and shape to render it capable of being inserted in the toe of the shoe and is mounted on the base or frame in such a manner as to permit it to be turned as the sewing progresses. At 14 is shown a needle which is straight and barbed. The work, which is designated A in the drawings, is fed by a feed point 5. At 6 is shown a shuttle which feeds the shuttle thread 7 and cooperates with the needle in the formation of the stitch. Inside the horn is a looper 8 through which the cop thread 19 is fed, and which also cooperates with the needle in the formation of the stitch. A takeup is shown at 20 (see Figures 1 and 4), and operates on the cop thread. All of the stitch-forming instrumentalities are actuated by a main shaft 27 rotatably mounted in the framework of the head of the machine. The needle 14 is mounted in the lower end of a reciprocating needle bar 21 guided in the frame of the head 13. Said needle bar is actuated by a cam lever 22 carrying a cam roll 23 in a cam groove 24 in a plate cam 26 of ordinary construction. The cam lever is connected to the needle bar by a link 25. The plate cam 26 is mounted on the main shaft 27 and actuates the needle bar in time with the other working instrumentalities of the machine. 85

The work feeding devices, the shuttle, and the parts associated with the latter specifically form no portion of the present invention, being covered by the claims of other applications filed by me as follows:—as to the shuttle; Serial No. 594,457, filed October 14, 1922; as to the shuttle raceway and associated parts; Serial No. 595,266, filed October 18, 1922; and as to the work-feeding devices; Serial No. 600,224, filed November 11, 1922. 95 100

For the purpose of the present descrip-

tion it will be sufficient to say that in its 5 operation the needle 14 comes up through the work with a loop of the cop thread 19 caught in its barb, whereupon the shuttle 6 is rotated and caused to pass through said loop, carrying with it the shuttle thread and removing said loop from the barb of the needle. The loop is formed about the 10 needle and is withdrawn from the shuttle 10 after the passage of the latter therethrough, and the stitch tightened, by the looper and takeup mechanism constituting the present invention and hereinafter described.

The horn 12 is hollow and of elbow shape 15 being mounted on a hollow base 85 which has a journal portion 112 rotatable in the frame of the machine. The horn is not positively rotated but can be swung by the operator as he sews around the edge of the 20 sole, and the hollow base contains and surrounds a portion of the operating mechanism for the looper and takeup. The horn has a flat upper surface 67 forming a work support, which is pierced at *k*, as indicated by 25 dotted lines in Figure 3, to permit the passage of the needle and cop thread. The work-supporting surface of the horn can be made very small to permit its insertion in the toe of a small shoe with as much freedom of movement as is possible under the 30 conditions.

The looper 8 is formed on the end of an 35 oscillating shaft 68 carried in bearings in the horn. The looper itself has an eye *n* and therefore is of the thread feeding type as distinguished from loopers which engage the thread at a certain point of the cycle of operations and are at other times disengaged therefrom. The looper shaft 68 is drilled 40 longitudinally to provide a passage 69, and the thread 19 passes through the passage, thence past the bent portion of the looper, thence through the eye *n*, and thence through the work. At 70 and 71 is shown a pair of 45 bevel gears which connect the lower end of the looper shaft 68 with the adjacent end of a shaft section 72 also mounted in bearings in the horn 12 and disposed at an angle to the shaft 68. The lower end of the shaft 50 72 is provided with a bevel gear 73 meshing with a gear 74 mounted on the upper end of the shaft 75. The shafts 72 and 75 and gears 70, 71, 73 and 74 are provided with axial passages similar to the passage 69 in 55 the shaft 68 and through which the cop thread 19 passes. The shaft 75 is journaled in a member 113 rigidly secured to the frame of the machine and has at its lower end a pinion 76 engaging a rack 77. The 60 rack 77 is connected to a bell crank 78 pivoted at 79 to the frame of the machine. This bell crank is operated by a rod 80 (see Figure 5) and a second bell crank 81, one arm of which is provided with a cam roll 82 operating in a groove in a cam 83 on the

main shaft 27. From the foregoing it will be seen that the movement produced by the cam 83 causes the looper shaft 68 to oscillate once for each cycle of operations of the machine.

The action of the looper will be readily understood from Figure 3. In this figure the needle 14 is shown at its lowest position, at which time its barb is below the top of the looper. When the looper oscillates 75 it passes about the needle, thereby laying the cop thread in or slightly above said barb. Thereafter when the needle rises the cop thread is caught by the barb and is carried up through the work, forming the loop. 80

The construction of the looper is such that it is contained within the hollow end of the horn and can oscillate without interfering with the needle or striking the work from which it is fully protected by the horn. In 85 practice the side of the horn adjacent the looper is cut away to make it easier for the operator to thread up the machine, but this cutaway portion is not sufficient to permit the shoe to interfere with the movement of 90 either the looper or the needle.

The takeup 20 operates on the top thread and comprises a laterally oscillating finger located in the space between the gears 73 and 74 which operate the looper shaft section 72. It is provided with an eye *m* through which the thread 19 passes. This takeup finger is fixed to a vertical shaft 84 journalled in the member 113 and is located outside the circumference of the bevel gear 74 and inside the circular housing 85 on which the horn is mounted. The shaft 84 is provided at its lower end with an arm 86 having therein a slot 87. This slot receives a pin 88 carried by an arm 89 on a shaft 90 journalled in the member 113 and having a second arm 91 connected by a link 92 to a slide 93. The slide 93 is operated by a bell crank lever 94 pivoted at 79. The bell crank lever 94 is operated by a connecting rod 95 connected to one arm 16 of a rock shaft 96 having a second arm 97 which carries a cam roll 98 travelling in the groove of a cam 99 mounted on the main shaft 27. 110

From the foregoing it will be seen that the takeup finger 20 enters the space between the bevel gears 73 and 74 and is moved out of said space to the position shown in broken lines in Figure 4, pulling the cop thread down vigorously and setting the lock of the stitch deeply into the channel of the sole. 115

It will also be seen that, by reason of the fact that the connections between the takeup or stitch-setter 20 and its operating mechanism outside the horn pass through the stationary member 113, said connections remain operative in all angular positions of the horn and are not affected by the rotation of the latter. 120 125 130

What I claim is:—

1. In a shoe sewing machine and in combination, a looper, operating mechanism therefor including a pair of intermeshing bevel gears, and a takeup finger located between said bevel gears.
2. In a lock stitch shoe sewing machine, in combination, a looper, operating mechanism therefor including a pair of intermeshing bevel gears, and a laterally oscillating takeup finger located between said bevel gears.
3. In a shoe sewing machine and in combination, a looper, operating mechanism therefor including a pair of intermeshing bevel gears each having a hole therethrough for the passage of the thread to the looper, and a takeup finger located between said bevel gears.
4. In a shoe sewing machine and in combination, a revolvably mounted horn, a looper having a shaft revolvably mounted inside said horn, a second shaft carried by the

horn, a pair of bevel gears connecting the proximate ends of said shafts, a third shaft 25 mounted in a stationary part of the machine, a pair of bevel gears connecting the proximate ends of the second and third shafts, there being thread passages through said shafts, and a takeup finger movable in 30 the space between said last mentioned pair of gears.

5. In a shoe sewing machine, in combination, a revolvably mounted hollow horn, a looper on a shaft revolvably mounted inside 35 said horn, a shaft at the base of said horn, a pair of intermeshing bevel gears one of which is on said shaft to operate the looper, a takeup finger movable in the space between said bevel gears, operating means for the 40 takeup finger, and a casing forming a bearing for the horn surrounding the takeup mechanism.

In testimony whereof I affix my signature.

JAMES H. REED.
